UNITED STATES PATENT OFFICE.

JOHN SOMMER, OF PEORIA, ILLINOIS.

LIQUID-FUEL BURNER.

Application filed July 22, 1922. Serial No. 576,516.

To all whom it may concern:

Be it known that I, JOHN SOMMER, a citizen of the United States, a resident of Peoria, in the county of Peoria and State of Illinois, have invented new and useful Improvements in Liquid-Fuel Burners, of which the following is a specification.

This invention has reference to liquid fuel burners for furnaces and has been designed particularly for use in connection with annealing or heat-treating furnaces, but may be used in connection with any furnace where such a burner would be adaptable.

15 The invention has for its principal object to provide a burner for liquid fuel and to combine such a burner with a door having a mixing chamber, said door adapted to cover the port leading to the combustion chamber of the furnace.

The invention has for a further object to provide a liquid fuel burner in combination with a chambered door adapted to cover the port leading to the combustion chamber 25 of a furnace and hingedly supported so that it may be moved to uncover the port, and to liquid fuel and air supplying means, the door having a swingable relation in connection with said air supplying means and in 30 the provision of a flexible connection in the oil supplying means to permit the door to be opened and closed without danger to said fuel supplying means.

A further object of the invention is to 35 provide a liquid fuel burner for furnaces including means disposed exteriorly of the furnace for regulating the liquid fuel nozzle relatively to the combined oil and air nozzle of the burner, and in the provision of means 40 for cleaning said liquid fuel nozzle.

That the invention may be more fully understood reference is had to the accompanying drawings forming a part of the description illustrating a preferred embodiment 45 of the invention, in which:—

Fig. 1 is a front elevation of a liquid fuel burner embodying my invention, the same being applied to a furnace, only a fragment of which is shown and including the air and liquid fuel lines;

Fig. 2 is an enlarged vertical sectional view thru the burner and associated parts as the same would appear if taken on the line 2—2 Fig. 1;

Fig. 3 is a cross-section in plan as the

same would appear if taken on the line 3—3 Fig. 1, the dotted lines illustrating the relation of the swinging door to the air lining, and

Fig. 4 is an enlarged vertical sectional view thru a portion of the air line and as the same would appear if taken on the line 4—4 Fig. 1.

Like characters of reference denote corresponding parts thruout the figures.

In Figs. 1, 2 and 3, 1 designates the wall of a furnace of either an annealing, a heat-treating or other furnace in connection with which a liquid fuel burner is adapted to be used; said wall being provided with a port 70 or a fire-box 2 designed to have communication with the combustion chamber of the furnace.

Embedded in the wall of the furnace and disposed preferably in vertical position on either side of the port 2 are angle irons 3 and to these angle irons may be bolted or otherwise suitably secured a face-plate 4 provided with an opening 5, the wall of said opening constitutes a flange 6 extending outwardly from the body of the face-plate. The face-plate is provided with a bearing 7.

The liquid fuel burner, as previously stated, includes in its structure a chamber door having a hinged connection with the air line of the furnace to adapt it to be swung to position over the port 2 or away therefrom as occasion may require. The door is designated 8 and is formed or pro-

vided with an air chamber 9 the inlet to which comprise a boss or enlargement cast in the door having a threaded opening 10 to receive an elbow 11 connected by a coupling 12 to a pipe section 13 in the air line. The top and bottom and side walls forming the

chamber 9 of the door are tapered or inclined as at 14, see Figs. 2 and 3, and said tapered walls merge into a flange 15 on the front wall, which, when the door is in the closed position shown in Fig. 2, abuts

with the outer edge of the flange 6 surrounding the opening 5 in the face-plate 4 and thus embraces the chambered portion of the door, which, when closed is housed within said flange opening of the face-plate

and the tapering of the top and bottom and side walls of the door eliminates any possibility of the door sticking due to expansion and insures a tight connection. The

inner wall 16 of the door is formed or pro-

vided with a burner nozzle 17 having an orifice 18 the inner wall of which is tapered as shown at 19 for a purpose to be more fully explained, and when said door is closed the 5 nozzle fits within and is centered approximately axially of the fuel port 2 leading into the furnace. The outer wall of the door is provided with a threaded opening 20 disposed in axial alignment with the 10 nozzle 17, and in said threaded opening is screwed an adjusting nut 21 thru which is carried a tube 22 on the inner end of which there is detachably connected a tip 23 having the liquid fuel orifice 24; the face 15 of the tip being beveled or tapered as at 25 conforming substantially to the inner tapered surface 19 of the burner nozzle 17, it being understood, as will be described, 20 that the tip 23 is adjustable in the nozzle 17 for the purpose of regulating the atomization 25 of the fuel. As shown in Fig. 2 the chamber of the nozzle is much larger than the diameter of the tip 23 to provide for the 30 passage of air around the tip and for its mixture with the fuel as they pass through the orifice 18 in the burner nozzle 17. I prefer to construct the door with a baffled plate 26 shown in dotted lines in Fig. 1 for the purpose of providing a sinuous 35 channel for the passage of the air from the time it enters the chambered door until it is discharged into the burner nozzle to be mixed with the liquid fuel. The tube 22 is preferably connected with a T-coupling 27 and to the angular elbow of said coupling is connected a pipe 28 in the liquid fuel line. A lock nut 29 is threaded on the sleeve 22 to hold it in adjustable connection with the 40 coupling 27, and a lock nut 30 also on the sleeve 22 regulates the position of the sleeve in its relation to the adjusting nut 21 for securing the tube 22 and its tip 23 in their proper adjusted relation to the burner nozzle 17. Carried within the tube 22 and 45 through the coupling 27 is a cleaning rod or stem 31, the inner end of which is tapered or pointed, as shown in Fig. 2, and adapted to be inserted into and withdrawn from the orifice 24 in the tip 23 for cleaning the orifice in the event of its becoming clogged. 50 The outward movement of the stem or rod 31 is limited by a shoulder 32 on the rod which abuts with a wall in the coupling 27, and said rod or stem 31 is normally held in its outward position by means of a spring 55 33 encircling said rod or stem between a knob 34 on the end of the stem and a bushing 35 connected with the coupling 27. From the foregoing it is obvious that pressure 60 applied to the knob 34 will force the rod or stem 31 inwardly for the purpose of cleaning the orifice 24 in the tip 23, and when this pressure has been relieved the spring 33 will act to retract the rod or stem 65 31 and move it to its outward or normal posi-

tion shown in Fig. 2. The adjusting nut 21 is formed with a sleeve 36 the end of which is adapted to bear against the tip 23, as shown in Fig. 2. When it is desired to adjust the tip 23 in relation to the burner nozzle 17, said adjusting nut 21 may be turned so as to force the tip 23 and the tube 22 to the desired position, the bevel face 25 of the tip permitting it to be brought into juxtaposition with the beveled surface 19 of the burner nozzle if so desired, and removed a suitable distance therefrom. To remove the tip, the lock nut 30 will be turned, as well as the adjusting nut 21, when the tube 22 and the tip 23 may be retracted, the lock 80 nut 30 then being screwed up to hold the parts in such adjusted relation.

The air line includes the main conduit 37 to which is coupled in any suitable manner a pipe 38 which preferably is disposed in a vertical position in front of the furnace. The lower end of said pipe 38 is connected by suitable couplings 39 with the lower end of a vertically disposed pipe 40. This latter pipe passes up thru the bearing 7 on the face-plate 4, and also up thru an ear 41 connected to the door 8, said ear 41 serving as a hinged member, and is intended to center the door on the pipe 40 and to oscillate thereon. To the upper end 95 of the pipe is connected a coupling member 42 provided with a beveled end 43 affording a seat against which bears the lower end of the pipe section 18, previously referred to. With this construction the 100 weight of the door is carried on the coupling 42 and when the door is swung the pipe 13 turns on the beveled end 43 of said coupling 42, the meeting surfaces of the coupling 42 and the pipe 13 acting as a ground joint. Having a threaded connection with the 105 coupling 42 and disposed longitudinally in the pipe 13 and around which such pipe oscillates is a short section of pipe 44 thru which the air passes to and thru the couplings 12 and 11 into the chambered door 8, the inner pipe 44 preventing any leakage at the joint formed between the pipe 13 and the coupling 42.

As the door is swung the pipe section 28 in the fuel line must swing therewith, and I therefore provide in such pipe a suitable flexible coupling 45, see Fig. 1. The pipe 28 is connected with a feeder 46 receiving its supply of liquid fuel from any suitable source, and the feed pipe 28 preferably at a point between the flexible coupling 45 and the feeder 46 is provided with a regulator valve 47.

By providing a burner such as herein described for liquid fuel and combining such a burner with a door covering the fuel inlet port and having means for regulating the atomization and cleaning the fuel tip exteriorly of the furnace, I gain several 125 130

advantages over the ordinary type of liquid fuel burner. It is always necessary with liquid fuel burners of the type used on annealing or heat-treating furnaces and the like, to clean the oil nozzle at irregular intervals due to the clogging of the small orifice thru which the liquid fuel is ejected into the furnace either from some heavy matter in the liquid fuel itself, or due to carbonizing of the fuel from the radiated heat of the furnace. In the burner of the ordinary type it is necessary to practically dismantle and disconnect it in order to clean this orifice. However, with my burner this is made a comparatively simple matter as has been described. Furthermore, in order to adjust the degree of atomization on an ordinary burner it is necessary to do this from the furnace side of the burner which introduces the same difficulties mentioned in connection with the cleaning of the orifice. In my burner this trouble is obviated because all adjustments can be made with the burner in position and from the exterior side of the burner. Furthermore, it is necessary at irregular intervals to be able to clean out or have access to the fuel inlet port of the combustion chamber, and any ordinary burner must be completely dismantled in order to do this, or else disconnected from the fuel and air supply systems. With my burner this is easily accomplished by merely turning a valve to shut off the oil and then swinging open the door. Furthermore, it is very difficult with the ordinary burner to so enclose it in the furnace wall as to prevent the infiltration of excess air around the burner, owing to the many difficulties which have previously been mentioned in connection with the dismantling and disconnecting of the burner. With my burner it is obvious that such excess infiltration is completely obviated. An ordinary burner cannot be set in an iron plate because the radiated heat from the combustion chamber in a very short time buckles up the plate and cracks it. Furthermore, in order to get pre-heated air for the burner in the ordinary type it is necessary to pass the air pipe thru either the hot walls of the furnace, or some other part of the furnace where the air will be pre-heated. With my type of burner both these difficulties are avoided because the circulation of air in the door keeps the door cool and at the same time in extracting the heat from the door the plates become pre-heated and so aids in the combustion.

60 In Figs. 1 and 2 the door 8 is shown provided with a peep-hole 48 which may or may not be used, as desired.

What I claim is:

1. In combination with a door provided with a burner nozzle, an air line having a

vertical part the upper end of which is connected to the top part of the door to itself provide a combined upper pivotal support and an air conduit for the door, and means to pivotally connect the lower part of door 70 to said vertical part of the air line.

2. In combination with a door provided with a burner nozzle, a sectional air line having one section provided with a seat and having its other section connected to the door and rotatably supported on the seat so as to vertically support the door solely from the air line, and means connected to the door and movably connected to the vertical part of the air line to pivotally support the lower part of the door from the air line.

3. In a liquid fuel burner, in combination, a supporting face plate to cover the fuel inlet port of a furnace and having an opening therein surrounded by an outwardly projecting flange, a door to cover the opening in the face plate and adapted to fit within said surrounded flange and provided with an air circulating chamber therein, a burner nozzle in the inner wall of said door, an air line connected with said door and arranged to conduct air to the air circulating chamber thereon, means connecting the door to the air line and supporting the weight of 95 the same in a manner whereby the door has a swingable connection with said air line, and means connected to the door for conducting liquid fuel to the burner nozzle.

4. In a liquid fuel burner, in combination, 100 a supporting face plate to cover the fuel inlet port of a furnace and having an opening therein surrounded by an outwardly projecting flange, a door having an air circulating chamber and tapered top 105 and bottom and side walls adapted to cover the opening in the face plate and to fit within said surrounding flange, a burner nozzle in the inner wall of said door, a pipe supported in a vertical position on the front 110 of the face plate, said pipe adapted to conduct air to the burner nozzle in the door, means hingedly connecting door to said pipe and for carrying the weight of the door on the pipe, such connecting means 115 serving as a conductor of air from the pipe to the door, and other means connected to the door for conducting liquid fuel to the burner nozzle.

5. In a liquid fuel burner, in combination, 120 a supporting face plate to cover the fuel inlet port of a furnace and having an opening therein, a chambered door adapted to cover the opening in the face plate and provided with a burner nozzle, air conducting 125 means including a pipe disposed in a vertical position on the front of the face plate, a coupling connected to said pipe, pipe connections between said door and said coupling adapted to sustain the weight of the 130

door and swingable on said pipe and coupling, a coupling connected with the door for conducting liquid fuel to the burner nozzle thereof, and a feed pipe connected with said last mentioned coupling and adapted to be connected with a source of supply for liquid fuel.

6. In an apparatus of the character described, in combination, with a furnace having a fuel inlet port a face plate attachable to the wall of the furnace and having an opening coinciding with the fuel inlet port, a door adapted to fit within the opening in the face plate and to cover the fuel inlet port, a burner nozzle on said door, a main conduit for air, pipe connections between said conduit and said door, means in said pipe connection for sustaining the weight of the door and providing a hinged connection between the door and said pipe connections, a feeder for liquid fuel, means

connecting said feeder with the door for conducting the liquid fuel to the burner nozzle of the door, and a flexible connection in said last mentioned connection whereby the same may adapt itself to the swinging movement of the door.

7. In combination with a door provided with a burner nozzle, an air line having a lower vertical part provided with a seat and a fixed tubular part projecting above the seat, said air line also having an upper vertical part connected to the door and loosely telescoped over said tubular part and engaged on the seat to form a pivotal support for the door, and means to pivotally connect the lower part of the door to the air line.

In witness whereof I have hereunto affixed my hand this 20th day of July, 1922.

JOHN SOMMER.
